UNITED STATES PATENT OFFICE.

SAMUEL A. NEIDICH, OF EDGEWATER PARK, NEW JERSEY.

INK-RIBBON-WINDING MECHANISM.

Application filed July 29, 1925. Serial No. 46,823.

My invention relates to mechanism which may be advantageously employed in winding ink ribbons upon metal spools adapted for detachable connection with typewriting, billing, adding, and similar machines. Different lengths of such ribbons are required for different forms of such machines, and my invention provides means for adjustably varying the length of the ribbons thus wound and automatically indicating when the desired length is wound upon each spool.

The form of my invention hereinafter described includes means enabling the operator to instantly rigidly connect such a spool with the winding mechanism and instantly disconnect the same; means arranged to stop the winding mechanism; means which may be manually adjusted and set to predetermine the length of ribbon which shall be wound before the stop mechanism is caused to automatically operate; and means whereby said stop mechanism may be manually reset in operative position, after being automatically tripped. As such winding mechanism normally operates at high speed; I prefer to provide it with a brake mechanism which is automatically brought into operation when the stop mechanism is tripped, so as to check the momentum of the mechanism. My invention includes the various novel features of construction and arrangement hereinafter more definitely specified.

In said drawings: Fig. I is a front elevation of a convenient embodiment of my invention, including a fragmentary, somewhat diagrammatic, indication of the means whereby the stop mechanism may be manually reset after being automatically tripped.

Fig. II is a right hand end elevation of said winding mechanism.

Fig. III is a left hand end elevation of said winding mechanism.

Fig. IV is a transverse vertical sectional view of said mechanism, taken on the line IV, IV in Fig. V, in the direction of the arrows on said line.

Fig. V is a plan view of said mechanism, with the cover, shown in the preceding figures, removed.

Fig. VI is an end view of the spool clutch.

Fig. VII is a longitudinal sectional view of the spool clutch mechanism, detached from the winding shaft.

Fig. VIII is a transverse vertical sectional

view, taken on the line VIII, VIII in Fig. V, in the direction of the arrows on said line.

Fig. IX is a transverse vertical sectional view of said mechanism, taken on the line IX, IX in Fig. V in the direction of the arrows on said line.

Fig. X is a vertical sectional view of the electrically operative stop tripping device.

In said figures: 1 is the base frame of the winding mechanism in which the winding shaft 2 is journaled, preferably in ball bearings 3 and 4, as indicated in Figs. V and IX. Said winding shaft 2 has the pulley 6 rigidly connected therewith, whereby it may be rotated by the belt 7 which is arranged to be shifted on to the loose pulley 8, automatically, as hereinafter described.

As indicated in Fig. V; said winding shaft 2 is hollow and provided with the internal screw thread 9 at the front end thereof in which is detachably fitted the external screw thread of the spool clutch sheath member 10, best shown in Fig. VII. Said clutch member 10 has the longitudinal slot 11, best shown in Fig. VI, in which the clutch blade 12 is mounted to reciprocate longitudinally and radially. As best shown in Fig. VII; said clutch member 12 has the cam incline 14 at the lower edge thereof which rides over the front edge of the slot 11 in said clutch member 10, so that when said member 12 is withdrawn, to the right in Fig. VII, it is thrust radially outward, with respect to said clutch member 10. Said clutch member 12 has the screw threaded socket 15 at its rear end for engagement with the screw threaded front end 16 of the clutch rod 17, by which said blade 12 may be shifted longitudinally in its sheath 10. Said rod 17 is normally stressed in the direction of the arrows indicated in Figs. V and VII, by the spring 19 which abuts at one end against the case of the ball bearing 4 and at the other end against the collar 20 which is rigidly connected with said rod. It may be observed that movement of said clutch rod 17 in that direction thrusts the clutch blade member 12 radially outward with respect to said clutch sheath member 10, to rigidly clamp the ribbon spool 22 in connection with said winding shaft, by frictional engagement of said clutch members 10 and 12 with the inner surface of the

axial bore in the hub 23 of said spool, as indicated in Fig. V. However, said spool 22 may be instantly released from said clutch, by movement of said clutch rod 17 in the direction opposite to said arrows shown in Figs. V and VII, and such movement is effected by means of the yoke 25 which embraces said rod 17 between said collar 20 and the knob 26 which is internally screw threaded as a nut in engagement with the thread 27 on the rear end of said rod 17. As shown in Fig. V; said yoke 25 is rigidly connected at its other end with the chain bar 28 which is mounted to reciprocate in said base frame 1 and the bracket 29 rigidly connected with said frame, and is connected at its front end with the chain 31 which extends over the sheave 32 to the pedal 34, indicated in Fig. I. Said sheave 32 is journaled in the bracket 35 which is rigidly connected with said frame 1. It is to be understood that downward movement of said pedal 34 and chain 31 thrusts said clutch rod 17 forward so that the clutch blade 12 rides over the edge of said sheath 10, on its incline 14 and is thus permitted to radially retract from engagement with said spool; the connection of said blade with said rod tending to spring press said blade 12 against the edge of said slot 11, toward such retracted position.

I provide means to automatically stop the rotation of said winding shaft 2, as follows: Said belt 7 passes to the pulley 6 between the tines of the belt shifting fork 37, which is rigidly connected with the belt shifting lever 38 which is fulcrumed on the screw 39 in the bracket 40 rigidly connected with said base frame 1. Said lever 38 carries the brake shoe bracket 42 which is pivotally connected therewith by the screw 43 and faced with the brake shoe 45 which may be formed of leather or other material adapted to frictionally engage the adjacent face of said pulley 6 when said lever 38 is swung to the right in Fig. V. Such movement is conveniently effected by the spring bolt 46 which is mounted to reciprocate in the opposite sides of said base frame 1, as indicated in Fig. V, and pivotally connected with said lever 38 by the screw 47. Said bolt is encircled by the spring 49 which abuts at one end against said frame 1 and at the other end against the collar 50 which is rigidly connected with said bolt 46. Said spring 49 continually tends to thrust said spring bolt 46 to the right in Fig. V but is normally held by said belt shifting lever 38, in the inoperative position shown in Fig. V; in which said parts are detained by the detent latch lever 52 which is fulcrumed on the screw stud 53 projecting from said frame 1. Said latch 52 has the hardened hook piece 54 rigidly connected therewith to overhang and engage the right hand edge of said lever 38 as indicated in Fig. V, when said

latch is permitted to drop, of its own weight, to the position shown in Fig. VIII. However, when said detent latch lever 52 is uplifted to the position shown in Fig. IX; it releases said belt shifting lever 38 and permits said spring 49 to act, to thrust said belt shifting lever 38 to the right in Fig. V to shift said belt 7 from said pulley 6 to the loose pulley 8 on said winding shaft 2 so as to stop the positive rotation of the latter. However, the momentum of the parts would cause said shaft 2 to continue to rotate if it were not for the fact that such movement of the lever presents the brake shoe 45 in contact with the adjacent face of said pulley 6 against which it is pressed by said spring 49 to thus check and stop the rotation of said shaft 2 after said belt 7 has been shifted.

Said detent latch 52 may be uplifted to permit said belt 7 to be shifted and rotation of the shaft 2 stopped, as above described, by means of the manual trip lever 56 which, as indicated in Figs. V, VIII and IX, is fulcrumed on the screw stud 57 projecting from the outside of said base frame 1 and has its rear L-end extending below the end of said lever 52 which projects through said base frame 1.

However, I also provide an electrically operative tripping device including the casing 59 in which the trip lever 60 is fulcrumed and from which it extends beneath the end of said latch lever 52 as indicated in Figs. VIII and IX. The latter tripping device includes an electromagnet 61, indicated in Fig. X, having an armature 62 in operative relation with said trip lever 60 so that the latter is normally held in the position shown in Fig. VIII but is uplifted by its spring 63 to strike and uplift said latch lever 52, and thus disengage the latter from said belt shifting lever 38, whenever said electromagnet 61 is energized by closure of the circuit in which its conductors 64 and 65 are included.

The ink ribbon 67 is primarily wound in a large roll, from which it passes underneath the guide stud 68 between the guide collars 69, as indicated in Figs. I and IV. Said guide stud 68 is rigidly mounted in said base frame 1 and said collars 69 are axially adjustable thereon and provided with set screws 70 whereby they may be held in adjusted position in accordance with the width of said ribbon 67. Said ribbon 67 is thus directed over the roller 71 to said ribbon spool 22 to which its front end is connected in any convenient manner so that the ribbon is wound on said spool by the rotation of said shaft 2. Said roller 71 is rigidly connected with the outer end of the measuring shaft 73 which is journaled in said base frame 1, conveniently in the roller bearings 74 and 75 indicated in

Fig. IV. The tension of said ribbon 67 is such as to frictionally engage the ribbon with and turn said roller 71 and the measuring shaft so that the extent of the rotation of the latter corresponds with the extent of the ribbon which is thus caused to pass over and turn said roller 71. Said measuring shaft 73 is arranged to actuate an electric switch mechanism to close said circuit and stop said winding shaft if and when seven yards of ribbon have been wound on said spool 22 or twelve yards have been wound thereon, dependent upon manual adjustment of the switch mechanism, and as follows:

Said measuring shaft 73 has, rigidly connected therewith, the worm 77 which engages the teeth on the worm gear 78, which is mounted on the screw stud 79 projecting from said base frame 1 and is provided with the contact pin 80 projecting therefrom in the path of the adjustable contact arm 81; the latter being rigidly connected with the inner end of shaft 82 which is journaled in the insulating bearing 83 which is mounted in said base frame 1. Said shaft 82 has rigidly connected with its outer end the index arm 84 having the index pin 85 for engagement with any one of the three seats 87, 88 and 89, indicated in Fig. III, which are in the metal plate 90 which is also insulated from said base frame 1 by the insulating block 91 indicated in Figs. I and V. Said plate 90 has an electrical connection with said conductor 64 so that said contact arm 81 is the terminal of one side of said electrical circuit; the other side of said circuit being grounded upon said base frame 1 by way of said conductor 65 and a source of current 92, as indicated in Fig. V. It is to be understood that when said contact arm is manually set in the position indicated in dotted lines in Fig. IV, which corresponds with the position of the index arm 84 in which the index pin 85 engages the index seat 87 as indicated in Fig. III; said contact pin 80 carried by the worm gear 78 is adapted to contact with said arm 81 once during each revolution and thus close said circuit, actuate said trip lever 60 to release said latch lever 52 and thus stop the winding mechanism after seven yards of ink ribbon have been wound upon the spool 22.

Said measuring shaft 73 is also provided with the worm 94, rigidly connected therewith, engaging the teeth of the worm gear 95 which is provided with the contact pin 96 which projects in the path of said contact arm 81 when the latter is manually set in the position indicated in full lines in Fig. IV which corresponds with the position of the index arm 84 shown in Fig. III; in which the index pin 85 is engaged in the index seat 89. The construction and arrangement are then such that said stop circuit is closed once during each revolution of said worm gear 95

which is so proportioned that one revolution thereof corresponds with the winding of twelve yards of ink ribbon upon the spool 22.

When said index arm 84 is manually set with its index pin 85 engaged with the index seat 88, indicated in Fig. III; said contact arm 81 is intermediate of the paths of the contact pins 80 and 96 aforesaid so that neither of said contact pins can reach said contact arm 81 and, consequently, in that position of said contact arm 81, the winding mechanism may be operated indefinitely without being automatically stopped as above contemplated. I find it convenient to provide said worm gear 95 with the pointer 98 which is presented in a vertical direction when the mechanism is stopped as the result of contact of the pin 96 with said contact arm 81; it being understood that such stoppage is not absolutely instantaneous, as the momentum of the mechanism is such that it continues to turn to a certain extent even after the application of the brake shoe 45 upon the pulley 6 as above described. I also find it convenient to provide the pointer 100 upon the gear wheel 101 which is mounted to turn upon the screw stud 102 projecting inwardly from said frame 1 and has its teeth in mesh with the teeth of said worm gear 78; so that said pointer 100 is presented in vertical position when the winding mechanism is stopped as the result of closure of said circuit by contact of the pin 80 with said contact arm 81. Said pointers 98 and 100 merely facilitate the adjustment and manipulation of the winding mechanism by the operator.

In order to conveniently reset, to the normal position shown in Fig. V, said belt shifting lever 38, with the brake and other appurtenances thereof, above described; I provide said spring bolt 46 with the pin 104 for engagement with the arm 105 of the resetting lever 106 which is rigidly connected with the rock shaft 107 which is journaled in the opposite sides of said base frame 1. Said resetting lever 106 is provided with the chain 108 which may extend to a separate pedal or be connected with said pedal 34 as indicated in Fig. I. Moreover, I find it convenient to provide said tripping lever 60 with the chain 110, indicated in Fig. X, which may be connected to a separate pedal or be connected to said chain 108, as indicated in Fig. I. It is to be understood that if said chains 31, 108 and 110 are all connected to the single pedal 34 they may be of respectively different lengths and more or less slack; so that the respective operations effected thereby may be performed during different portions of the movement of said pedal 34.

Although I have found it convenient to use the specific form of my invention above described, it is obvious that various modifi-

cations may be made therein without departing from the essential features of my invention as defined in the appended claims. Moreover, it is obvious that the specific form of ribbon spool clutch above described is not essential to the operation of the other mechanism; as the winding shaft 73 may be provided with any suitable means for properly engaging any spool or other holder upon which the ribbon may be wound. Therefore, it is to be understood that I do not desire to limit myself to the precise details of construction and arrangement herein set forth.

15 I claim:

1. In ribbon winding mechanism, the combination with a base frame; of a rotary winding shaft journaled in said frame; clutch means on said shaft arranged to detachably engage the holder upon which a ribbon may be wound; means on said shaft whereby it may be rotated, including a tight pulley rigidly connected with said shaft; a loose pulley journaled on said shaft; a belt shifting lever fulcrumed in said frame, having a fork arranged to normally direct a belt in operative relation with said tight pulley; a brake bracket pivotally connected with said shifting lever, and faced with a shoe, arranged to frictionally engage the surface of said tight pulley when said shifting lever is pressed toward the latter; a spring bolt mounted to reciprocate in said frame transversely to said shifting lever and pivotally connected therewith; a spring encircling said spring bolt continually tending to press said shifting lever toward said tight pulley, to shift said belt to said loose pulley, and apply said brake; means arranged to detain said shifting lever against the action of said spring, including a detent latch lever, fulcrumed in said frame; and means arranged to trip and release said latch lever, to permit said shifting lever to be operated to both shift said belt and positively apply the brake, by said shifting lever, including a tripping lever fulcrumed exterior to said frame, and having one end extending beneath the projecting end of said latch lever.

2. In ribbon winding mechanism, the combination with a base frame; of a rotary winding shaft journaled in said frame; clutch means on said shaft arranged to directly detachably engage the holder upon which a ribbon may be wound; clutch operating means extending through said shaft, in coaxial relation therewith; a spring encircling said clutch operating means exterior to said frame and continuously tending to clutch said ribbon holder in cooperative relation with said shaft; means arranged to release said clutch, including a slide bar extending parallel with said shaft and having a flexible connector in cooperative

relation therewith; whereby said clutch may be released; means on said shaft whereby it may be rotated, including a tight pulley rigidly connected with said shaft; a loose pulley journaled on said shaft; a belt shifting lever fulcrumed in said frame, having a fork arranged to normally direct a belt in operative relation with said tight pulley; a spring bolt mounted to reciprocate in said frame transversely to said shifting lever and pivotally connected therewith; a spring encircling said spring bolt continually tending to press said shifting lever toward said tight pulley, to shift said belt to said loose pulley; means arranged to retain said shifting lever against the action of said spring, including a detent latch lever, fulcrumed in said frame; and means arranged to trip and release said latch lever, to permit said shifting lever to be operated to shift said belt, including a tripping lever fulcrumed exterior to said frame, and having one end extending beneath the projecting end of said latch lever.

3. In ribbon winding mechanism, the combination with a base frame; of a rotary winding shaft journaled in said frame; clutch means on said shaft arranged to detachably engage a holder upon which a ribbon may be wound; means on said shaft whereby it may be rotated, including a belt; means arranged to stop the rotation of said winding shaft, including a spring bolt mounted to reciprocate in said frame; a spring arranged to continually press said bolt in one direction; and a brake lever, carrying a brake shoe arranged to bear upon the flat side of said belt wheel, and operatively connected with said spring bolt; means arranged to detain said brake lever in inoperative position, against the action of said spring, including a detent fulcrumed in said frame; and means arranged to trip said detent to permit said spring to operate said brake, including a tripping lever fulcrumed to exterior of said frame; and an electromagnet, in operative relation with said tripping lever.

4. In ribbon winding mechanism, the combination with a base frame; of a rotary winding shaft journaled in said frame; coaxially reciprocatory clutch means on said shaft arranged to detachably engage a holder upon which a ribbon may be wound; means on said shaft whereby it may be rotated; means arranged to stop the rotation of said winding shaft, including a spring bolt mounted to reciprocate in said frame in parallel spaced relation with said shaft; a spring arranged to continually press said bolt in one direction; and a brake operatively connected with said spring bolt; means arranged to detain said brake in inoperative position, against the action of said spring, including a detent fulcrumed in said frame; and means arranged to trip said detent to

permit said spring to operate said brake, including a tripping lever fulcrumed exterior to said frame.

5. In ribbon winding mechanism, the combination with a base frame; of a rotary winding shaft journaled in said frame; clutch means on said shaft arranged to detachably engage a holder upon which a ribbon may be wound; means on said shaft 10 whereby it may be rotated, including a tight pulley rigidly connected with said shaft; a loose pulley journaled on said shaft; a belt shifting lever, arranged to normally direct a belt in operative relation with said 15 tight pulley; a brake member, carried by said shifting lever, and arranged to frictionally engage the flat side of said tight pulley when said shifting lever is pressed toward the latter; a spring bolt mounted to reciprocate in said frame transversely to said shifting lever and engaged therewith; a spring tending to press said shifting lever toward said tight pulley, to shift said belt to said loose pulley; means arranged to detain said shifting lever against the action of said spring, 20 including a detent latch lever, arranged to engage the edge of said shifting lever; and means arranged to trip and release said latch lever, to permit said shifting lever to be operated to shift said belt, including a worm 25 on said winding shaft and a worm gear engaging said worm.
6. In ribbon winding mechanism, the combination with a base frame; of a rotary winding shaft journaled in said frame; clutch means on said shaft arranged to reciprocate in coaxial relation with said shaft and detachably engage a holder upon which a ribbon may be wound; means on said shaft whereby it may be rotated, including a tight pulley rigidly connected with said shaft; a 30 loose pulley journaled on said shaft; a belt shifting lever, arranged to normally direct a belt in operative relation with said tight pulley; a spring bolt mounted to reciprocate in said frame transversely to said shifting 35 lever and engaged therewith; a spring tending to press said shifting lever toward said tight pulley, to shift said belt to said loose pulley; means arranged to detain said shifting lever against the action of said spring, 40 including a detent latch lever, arranged to engage the edge of said shifting lever; and means arranged to trip and release said latch lever, to permit said shifting lever to be operated to shift said belt, including a worm 45 on said winding shaft and a worm gear engaging said worm.

In testimony whereof, I have hereunto signed my name at Burlington, New Jersey, this twenty-first day of July, 1925.

SAMUEL A. NEIDICH.
